LESTER O. MARSTELLER, OF WILKINSBURG, PENNSYLVANIA, ASSIGNOR TO WESTINGHOUSE ELECTRIC & MANUFACTURING COMPANY, A CORPORATION OF PENNSYLVANIA.

TELEPHONE PLUG.

Application filed October 2, 1922. Serial No. 591,801.

My invention relates to telephone plugs, having particular relation to the connection of the telephone cord with the contacting elements of the plug.

In its broadest aspect, one object of my invention is to provide a telephone-plug structure carrying means whereby telephone tips may be removably connected to the contact portion of the plug structure without the use of tools or the necessity for removing any portion of said plug structure and, at the same time, insuring an exceptionally firm electrical contact and a smooth mechanical contact between the several elements. Another object of my invention is to provide a telephone-plug construction of simple, compact and rugged design which is susceptible of inexpensive quantity-production methods of manufacture with existing automatic machinery, the several parts of which may be made with a minimum expenditure of time and of money.

According to my invention, I provide a telephone-plug construction comprising a block of insulating material carrying contact-plug elements at one end thereof and cooperating socket contact elements at an opposite end, the socket elements being designed to removably and resiliently engage the tips of a telephone cord.

With these and other objects and applications in view, my invention further consists in the details of construction and arrangement hereinafter described and claimed and illustrated in the accompanying drawing, wherein

Figure 1 is a greatly enlarged longitudinal sectional view of a telephone-plug element embodying my invention, the section plane being indicated by the line I—I of Fig. 2.

Fig. 2 is an end elevational view of the structure shown in Fig. 1.

Fig. 3 is a view similar to Fig. 2, but with the cap removed, illustrating one form of resilient contact-socket element applicable to the structure of Fig. 1.

Fig. 4 is an enlarged detail view of the socket element before bending.

In the illustrated embodiment of my invention is shown a cylindrical block 1 of bakelite, hard rubber or other insulating

material, having opposite ends 2 and 3. The opposite ends 2 and 3 of the block are connected by a perforation 4 which is countersunk at the end 2 to form a recess 5. The other end 3 of the block is provided with borings 6 and 7 which are countersunk to form recesses 8 and 9.

A core member 11 of brass or other conducting material is positioned in the perforation 4 and extended beyond the ends 2 and 3 of the block 1 to form projections 12 and 13, respectively. The projection 12 may terminate in a contact knob 14 having a shoulder portion 15. A tubular member 16 of brass or other conducting material encloses a material part of the projecting portion 12 of the core member 11 between the base of the recess 5 and the shoulder portion 15 of the knob 14. The tubular member 16 is insulated from the core member 11 by means of an insulating spacing member 17 interposed therebetween and by means of a washer 18 between the end of the tubular member 16 and the shoulder 15 of the knob 14. The contacting surfaces of the plug construction just described are formed by the knob 14 and the outer exposed surface of the tubular member 16.

The recess portions 8 and 9 of the borings 6 and 7, respectively, are designed to receive socket contact elements 19 and 21, respectively, while the remaining portions of the borings 6 and 7 provide space for the ends 22 and 23 of co-operating plug elements 22 and 23 extending beyond the socket elements. By way of illustration, the contact elements 19 and 21 are shown in the form of annular helical-spring members having terminal tabs 24 and 25, respectively. The annular helical-spring members may be formed by bending a single helical-spring member 26, as shown in Fig. 4, into the form of a ring. The springs may be made of such material as phosphor-bronze or stainless steel, preferably the latter since it admits of a heating treatment necessary in some forms of spring mountings.

A cap member 27 is employed for securing the spring-socket elements in position and is provided with perforations 28, 29 and 31 corresponding in diameter and in position to the borings 6 and 7 and the

perforation 4 in the main supporting block 1, respectively. Adjacent to the boring 7 in the main supporting block 1 is an auxiliary perforation 32 which extends parallel 5 to the main perforation 4 and is designed to receive the terminal tab 25. The cap member 27 is also provided with an auxiliary perforation 33 designed to receive the terminal tab 24 of the spring element 19. 10 In assembling the several socket parts just mentioned, the annular springs 19 and 21 are first fitted into the recess 8 and 9, respectively, and the terminal tab 25 is caused to extend through the auxiliary perforation 15 32. The terminal tab 25 is then secured in electrical contact with the tubular plug element 16 by inserting the tab 25 between the side of the recess 5 and the adjacent surface of the tubular member 16, thereby connecting the socket receptacle 21 to one of the contact elements 16 of the plug construction. The members 1 and 27 are then placed together, with the several perforations and openings in alignment. The portion 13 of 20 the core member 11, which extends beyond the end of the block 1, is threaded to receive a clamping nut 34. The several foregoing portions of the construction may readily be secured in position on screwing 25 the clamping nut 34 into engagement with the outer surface of the cap member 27.

The terminal tab 24 of the socket element 19 is caused to extend through the auxiliary perforation 33 in the cap member 27 and is 30 secured to the core member 11, thereby connecting the remaining contact-plug element to the socket element 19. As a matter of convenience, the cap member 27 may have a diameter slightly greater than that of the 35 main supporting member 1 to provide gripping means for removing the plug construction from a co-operating socket (not shown).

In operation, the tips 22 and 23 of a telephone cord 35 are first actuated into engagement with the socket elements 19 and 21, respectively, entering the same from the outer side of the cap member 27. The tips 22 and 23 are then held in sliding contact with the 40 socket elements. The foregoing construction is particularly applicable to radio apparatus, inasmuch as it permits a single telephone plug element to serve as a terminal connection for a loud-speaking device or 45 for an ordinary telephone receiver without the necessity of removing the plug structure or any parts thereof.

While I have shown only one embodiment 50 of my invention, for the purpose of describing the same and illustrating its applications, it is apparent that various modifications may be made in the constructional details thereof without departing from the spirit and scope of my invention. I desire, 55 therefore, that only such limitations shall be

made thereon as are demanded by the prior art or as are specifically indicated in the claims.

I claim as my invention:

1. In combination, a core member, a tubular member enclosing said core member, a tubular insulating element interposed between said two members, said two members having exposed contacting surfaces, an insulating block having opposite ends and provided with a countersunk perforation extending therebetween, said members and element being positioned in the countersunk portion of said perforation, said core member extending through said perforation to the remaining end of said block, said latter end having a pair of spaced borings, a socket contact element individual to each boring and adapted to removably and resiliently receive a plug, and means electrically connecting said members and said socket elements, respectively. 70 75 80 85

2. In combination, a core member, a tubular member enclosing said core member, a tubular insulating element interposed between said two members, said two members having exposed contacting surfaces, an insulating block having opposite ends and provided with a perforation therebetween, said perforation being countersunk at one end to receive said members and element, said core member extending through said perforation to the remaining end, means co-operating with said core and said block, whereby said members and core are rigidly secured in position, said last mentioned end having a pair of spaced countersunk borings, laterally resilient contact socket elements positioned in the countersunk portion of each boring, a cap having complementarily aligned perforations for securing said socket elements in position and means for electrically connecting said members and said socket elements, respectively. 90 95 100 105

3. In combination, a core member, a tubular member enclosing said core member, a tubular insulating element interposed between said two members, said two members having exposed contacting surfaces, an insulating block having opposite ends and provided with a perforation therebetween, said perforation being countersunk at one end to receive said members and element, said core member extending through said perforation to the remaining end, said last mentioned end having a pair of spaced countersunk borings, said block having an auxiliary perforation disposed immediately adjacent to one boring, a resilient contact element disposed in the countersunk portion of each boring and having terminal tabs extending from said block through said auxiliary perforation and through said boring, respectively, said tabs being connected to said tubular member and to said core mem- 110 115 120 125 130

ber, respectively, and means for securing plug elements extending from one of said members and connected respectively to said terminal tabs, and means for securing the parts in position.

4. In combination, a member having a plurality of countersunk borings, a second member having complementarily arranged perforations, each countersunk boring having an auxiliary guideway, a resilient tension socket element disposed in each countersunk portion and having terminal tabs

25

extending through said auxiliary guideways, a pair of contact plug elements extending from one of said members and connected respectively to said terminal tabs and means co-operating with the several parts for securing the same in position.

5. In combination, a member having a plurality of countersunk borings, a second member having complementarily arranged perforations, an annular helical contact element disposed in each countersunk portion and having terminal tabs, a pair of contact plug elements extending from one of said members and connected respectively to said terminal tabs, and means for securing the parts in position.

20

15

20

6. In combination, a member of cylindrical shape having a plurality of countersunk borings, a second cap member having complementarily arranged perforations, the diameter of said cap being greater than that of said cylindrical member, laterally resilient socket contact elements disposed in each countersunk portion and having terminal tabs, a pair of contact plug elements extending from one of said members and connected respectively to said terminal tabs, and means for securing the parts in position.

In testimony whereof, I have hereunto subscribed my name this 16th day of September, 1922.

LESTER O. MARSTELLER.
